REUBEN C. BAKER, OF COALINGA, CALIFORNIA, ASSIGNOR TO BAKER OIL TOOLS, INC.,
OF HUNTINGTON PARK, CALIFORNIA, A CORPORATION OF CALIFORNIA

WELL PUMPING UNIT

Application filed May 16, 1928. Serial No. 278,165.

This invention relates to deep well pumping apparatus and particularly pertains to a pumping unit for operating deep well pumps.

It is the principal object of the present invention to provide a generally improved pumping unit for deep well pumps by means of which the mechanical well load and the fluid load will be properly and entirely counterbalanced so as to minimize the power expended in operating the pump.

Another object of the present invention is to provide a pumping unit having a hoist mechanism operatively associated with this power plant for pulling the well.

In carrying out the invention into practice I provide a pumping unit having an oscillatory walking beam and what I prefer to term a fulcrum beam carrying a counterbalance at one end and operatively bearing against the walking beam at the other end. Means are provided for automatically adjusting the position of the counterweight on the fulcrum beam so as to counterbalance the fluid load on the up stroke of the pump in addition to the mechanical well load. This counterweight can also be adjusted to accommodate different well loads.

One form which the invention may assume is exemplified in the following description and illustrated by way of example in the accompanying drawings, in which:

Fig. 1 is a side elevation of a pumping unit embodying the preferred form of my invention.

Fig. 2 is a diagrammatic view in side elevation of the pumping unit showing the relative positions of the operating parts upon the down stroke of the walking beam.

Fig. 3 is a fragmentary view in perspective showing the construction of the crossheads, crosshead guides and the connection between the fulcrum beam and the walking beam.

Fig. 4 is a fragmentary view in plan showing the manner in which the counterweight is mounted on the fulcrum beam and connected with the counterweight crosshead.

Fig. 5 is a view in transverse section through the apparatus taken on line V—V of Fig. 1.

Fig. 6 is a view in transverse section

through the unit taken on line VI—VI of Fig. 1 and disclosing the mounting of the hoist mechanism.

Fig. 7 is a view in plan section.

Referring more particularly to the accompanying drawings, 10 indicates a well pumping unit for deep wells having a base structure 11 mounted either on the floor of the derrick or on a suitable foundation contiguous to the mouth of the well. The base 11 may be of any preferred design but is here shown as constructed of two longitudinal channel beams arranged in parallelism at a spaced distance apart and rigidly connected by suitable transverse members.

Arranged horizontally and transversely of the base 11 at the forward end thereof is a drive shaft 12 journaled in suitable bearings secured on the base. To drive the drive shaft 12 I provide a motor 14 having a pinion 15 keyed or otherwise secured on its shaft. This pinion 15 is in mesh with a spur gear 16 secured on a jack shaft 17 arranged horizontally and transversely of the base intermediate the drive shaft 12 and the motor 14. The jack shaft 17 is also fitted with a pinion 18 which is in mesh with a gear 19 secured on the drive shaft 12.

Through the medium of the gear train just described operation of the motor 14 will drive the drive shaft 12 at the preferred rate of speed. It is understood, however, that I may substitute other means for driving the drive shaft; that is, an internal combustion engine or other power plant may be substituted for the motor 14 or the drive shaft 12 may be driven by a pulley from a countershaft if it is preferred. In the present manner of construction, however, the pumping unit is entirely self-contained.

Secured at opposite ends of the drive shaft 12 is a pair of aligned cranks 20. These cranks 20 are connected to the lower ends of vertically reciprocal connecting rods 21. Arranged at the forward end of the unit and at opposite sides thereof in transverse alignment is a pair of crosshead guides 22 of any suitable construction. Crossheads 23 are mounted in these guides for vertical reciprocation. A transverse shaft 24 extends trans-

versely between the guides and is connected to the crossheads. The opposite ends of this shaft 24 are journalled in bearings 25 on the connecting rods 21, so that vertical reciprocation of the connecting rods will vertically reciprocate the crossheads 23 and the shaft 24.

It is, therefore, obvious that upon operation of the motor 14 that the drive shaft 12 will be driven to operate the cranks 20 and that the rotation of these cranks 20 will be translated by the connecting rods 21 into vertical reciprocation of the connecting rods and the crossheads 23.

Arranged centrally and longitudinally of the pumping unit at the top thereof is a walking beam 26 pivotally connected at its rearmost end to a pair of upright walking beam compensating arms 27. These latter are pivoted at their lower ends to the base 10 to compensate for the movement of the walking beam. It should be stated that although the walking beam 26 oscillates in a vertical plane its forward end which is connected to the polish rod must travel in a true vertical path, necessitating that the compensating arms 27 be permitted a certain amount of oscillation.

The walking beam 26 as shown in the drawings extends centrally between the crosshead guides 22 and over the shaft 24. At the underside of the walking beam at a point in vertical alignment with the shaft 24, the walking beam is fitted with a saddle 28 which bears on a bearing member 29 carried by the shaft 24. This bearing member also bears on a saddle 30 carried upon the forward end of a fulcrum beam 31 arranged below the walking beam in parallelism therewith. At a point intermediate its ends and on the underside thereof this fulcrum beam 31 is provided with a saddle 32 which bears on a shaft 33 carried by two upright fulcrum compensating arms 34. These latter arms are pivotally supported on the base as indicated by the numeral 35.

At the rearmost end of the fulcrum beam 31 a counterweight 36 is slidably disposed. This counterweight 36 is fitted with rollers 37 bearing on the beam 31, enabling the counterweight to be reciprocated along the beam. Forwardly of the counterweight 36 and guided on the fulcrum beam 31 for reciprocation is a counterweight crosshead 38.

A screw shaft 39 extends longitudinally of the fulcrum beam 31 and is collared at its forward end to the counterweight crosshead 38. This screw shaft 39 extends longitudinally through the counter weight 36 and is threaded to a feed nut 40 rigidly secured to the counterweight 36. At its rearmost end the screw shaft 39 is fitted with a crank 41 to revolve the shaft. By revolving the shaft, the counterweight 36 will be moved toward or away from the crosshead 38, depending upon the direction of rotation of the shaft. In this manner the effective position of the cross-

head on the fulcrum beam 31 may be adjusted to accommodate different well loads.

The counterweight crosshead 38 is connected by a connecting rod 42 to the upper ends of the connecting rods 21 so that the position of the counterweight 36 will be adjusted along the fulcrum beam 31 automatically upon operation of the cranks 20. The purpose of this will be hereinafter set forth.

A further adjustment is provided by providing means for adjusting the stroke of the connecting rod 42. This means comprises three points of connection indicated by the numeral 44 between the connecting rod 42 and the upper ends of the connecting rods 21.

It is obvious that when the point of connection between the forward end of the connecting rod 42 and the upper ends of the connecting rods 21 is changed, the stroke of the counterweight 36 will be altered.

In operation of the pumping unit, it is constructed and assembled as illustrated in the drawings and the screw shaft 39 is operated to adjust the position of the counterweight so that it will be in the proper position to compensate for the well load to be carried. Likewise, the point of connection between the forward end of the connecting rod 42 and the upper ends of the connecting rods 21 is determined by the well load.

Upon rotation of the motor 14, the drive shaft 12 will be driven to vertically reciprocate the connecting rods 21. Vertical reciprocation of these rods will reciprocate the shaft 24 and through the medium of the bearing member 29 cause oscillation of the walking beam 26 and the fulcrum beam 31. Upon the upward stroke of the connecting rods 21, the entire weight of the well load including the fluid load will be imposed upon the end of the walking beam. This load, however, will be entirely counterbalanced by the counterbalance 36 because the forward end of the fulcrum beam 31 will bear upwardly against the forward end of the walking beam.

I desire to point out that upon commencing the upward stroke the counterbalance 36 will be in its farthest outermost position so as to impose its maximum counterbalancing effect on the walking beam during the latter's upward stroke. This is due to the fact that the position of the connecting rods 21 will be such as to maintain the counterweight crosshead 38 in its rearmost position on the fulcrum beam 31.

The reason for changing the position of the counterweight during the cycle of operation of the walking beam is to counterbalance the fluid load imposed on the up stroke of the pump. In other words, the counterweight 36 in its innermost position is sufficient to counterweight the mechanical well load and when in its outermost position it is

sufficient to counterbalance the mechanical well load and the additional fluid load.

After the upward stroke of the walking beam has been completed, the counterweight 36 will be drawn inwardly toward the fulcrum point of the fulcrum beam 31 because on the downward stroke of the walking beam it is only necessary to counterbalance the mechanical well load.

It is thus obvious that I have provided automatically operating means for adjusting the effective position of the counterweight during the cycle of operation of the walking beam, so as to properly counterweight the load imposed upon the beam.

To accommodate different fluid loads the stroke of the counterweight on the fulcrum beam 31 may be altered by changing the point of connection between the connecting rod 42 and the connecting rods 21. By changing this stroke different fluid loads may be properly counterbalanced. Also to accommodate different well loads, the hand crank 41 may be operated to adjust the position of the counterweight 36 on the beam 31. By changing the position of the counterweight its effectiveness in counterbalancing the well load is changed and therefore different well loads may be properly counterbalanced.

In the present instance I have fitted the pumping unit with a hoist mechanism indicated by the numeral 46, which hoist mechanism comprises a drum 47 having the usual brake 48 and clutch 49. To drive the drum I provide a pinion and gear 50 and 51, the former being relatively fixed to a sprocket 52. This sprocket 52 is connected by a chain 53 to a sprocket 54 secured on the jack shaft 17, so that when the motor 14 is in operation the pinion 50 and gear 51 may be revolved by the motor. The clutch 49 is interposed between the gear 51 and the drum 47 so that when this clutch is engaged the drum 47 will be revolved by the motor.

The hoist mechanism 46 is utilized in pulling the well. To utilize the hoist mechanism it is only necessary to remove the polish rod connecting mechanism 55 and remove the saddle 56 from the end of the walking beam, so that the polish rods will be free from the walking beam. The pull rope is then connected to the polish rods and the hoist mechanism operated to pull the well.

From the foregoing it is obvious that I have provided a very efficient well pumping unit wherein the well load and the fluid load will be entirely and properly counterbalanced. Also, I have provided a pumping unit wherein the same power plant may be utilized to actuate the pump or to pull the well.

While I have shown the preferred form of my invention, it is to be understood that various changes may be made in its construction by those skilled in the art without depart-

ing from the spirit of the invention as defined in the appended claims.

Having thus described my invention, what I claim and desire to secure by Letters Patent is:

1. A pumping unit comprising an oscillatory member adapted to be connected to the polish rod of a pump to operate the same, a beam pivotally supported intermediate its ends beneath the oscillatory member, a counterweight on said beam at one side of its pivotal point, the other side of the beam opposite the counterweight bearing against the underside of the vertically movable member whereby the well load imposed upon the vertically movable member will be counterbalanced by the counterweight, means for automatically adjusting the position of the counterweight on the beam relative to its pivotal point whereby to accommodate changes in well load during the cycle of operation of the movable member.

2. A pumping unit comprising an oscillatory walking beam adapted to be connected to the polish rod of a pump to operate the same, a beam pivotally supported intermediate its ends beneath the walking beam, a counterweight on said beam at one side of its pivotal point, the other side of the beam opposite the counterweight bearing against the underside of the walking beam whereby the well load imposed upon the walking beam will be counterbalanced by the counterweight, means for automatically adjusting the position of the counterweight on the beam relative to its pivotal point whereby to accommodate changes in well load during the cycle of operation of the walking beam, and other means for adjusting the position of the counterweight on the beam to accommodate different well loads.

3. A pumping unit comprising an oscillatory walking beam, a second beam pivotally supported intermediate its ends beneath the walking beam, a counterweight on the second beam at one side of its pivotal point, the other side of the second beam opposite the counterweight bearing against the underside of the free end of the walking beam whereby the load imposed on the walking beam will be counterbalanced by the counterweight, means for automatically adjusting the position of the counterweight on the second beam to accommodate changes in well load during each cycle of operation of the walking beam.

4. A pumping unit comprising an oscillatory walking beam pivotally supported at one end and adapted to be connected with the polish rod of a pump at its free end, a second beam disposed below and parallel to the walking beam, said second beam being pivotally supported at a point intermediate its ends, a counterweight at one end of said second beam, the other end of said second

beam bearing against the underside of the free end of the walking beam, means for automatically adjusting the position of the counterweight on the second beam to accommodate changes of the well load during each cycle of operation of the walking beam.

5. A pumping unit comprising an oscillatory walking beam pivotally supported at one end and adapted to be connected with 10 the piston rod of a pump at its free end, a second beam disposed below and parallel to the walking beam, said second beam being pivotally supported at a point intermediate its ends, a counterweight at one end of said 15 second beam, the other end of said second beam bearing against the underside of the free end of the walking beam, means for automatically adjusting the position of the counterweight on the second beam to accommodate changes of the well load during 20 each cycle of operation of the walking beam, and other means for adjusting the position of the counterweight on the second beam to accommodate different well loads.
